CLAIM

The ornamental design for a frame for a disk harrow or similar implement, as shown and described.

DESCRIPTION

FIG. 1 is a rear perspective view of a frame for a disk harrow or similar implement, showing our new design;
FIG. 2 is a top view thereof;
FIG. 3 is a left side view thereof;
FIG. 4 is a right side view thereof;
FIG. 5 is a front view thereof;
FIG. 6 is a rear view thereof.

The broken lines showing of the disk harrow in FIG. 1 is for illustrative purposes only and forms no part of the claimed design.
